(57) **CLAIM**

The ornamental design for a blow nozzle with a plurality of holes, as shown and described.

DESCRIPTION

FIG. 1 is a perspective view of a blow nozzle with a plurality of holes, according to an embodiment of the new design; FIG. 2 shows a top view of the blow nozzle with a plurality of holes of FIG. 1;

FIG. 3 shows a bottom view of the blow nozzle with a plurality of holes of FIG. 1;

FIG. 4 shows a front view of the blow nozzle with a plurality of holes of FIG. 1;

FIG. 5 shows a left/right view of the blow nozzle with a plurality of holes of FIG. 1;

FIG. 6 shows a back view of the blow nozzle with a plurality of holes of FIG. 1;

FIG. 7 shows the blow nozzle of FIG. 1 inserted into a preform for a container; and,

FIG. 8 shows a front view of a blow nozzle with a plurality of holes, according to a second embodiment of the new design.

The broken lines shown represent portions of a blow nozzle with plurality of holes and forms no part of the claimed design.

1 Claim, 4 Drawing Sheets
